Minneapolis, Minn., a corporation of Delaware

Application February 16, 1939, Serial No. 256,737

16 Claims.

(Cl. 236—68)

This invention relates to a simplified control system for fuel burners and incorporates a plurality of thermo-couples which provide certain novel functions with safety shut-down features in the event of ignition failure.

In fluid fuel burner control systems employing pilot burners, it is customary to provide some means for interrupting the flow of fuel to the main burner if the pilot burner is extinguished. In certain cases, this means for interrupting the fuel flow has taken the form of an electrically operated control device which is energized by a thermo-couple exposed to the pilot burner flame. Such an arrangement has the advantage that it is independent of any external power supply and permits the safe manual operation of the burner before electrical wiring has been installed in the house or during periods of power failure. It has been proposed to further extend this idea by using a thermopile instead of a thermo-couple so as to increase the current available and to then place various condition responsive switches in the connections between the thermopile and the control device so as to provide a complete electrically operated control system independent of an external power supply and employing only one electrically operated control device. Such an arrangement, however, has the disadvantage that it is impossible to provide a thermopile small enough to be used with a conventional pilot burner which is still capable of generating a current adequate for such purposes. The condition responsive switches accordingly must have an extremely low contact resistance which cannot be maintained as they become worn out with use. Furthermore, certain features desirable in a control system such as "heat anticipation" cannot be used in such an arrangement.

It is an object of the present invention to provide an electrically operated control system wherein only one electrically operated control device is employed and wherein two thermo-couples are employed for actuating this control device, a first of which is responsive to pilot flame conditions and the second of which is controlled in accordance with other controlling conditions.

It is a further object of the present invention to provide such a system wherein the second thermo-couple is heated by an external heater, the energization of which is controlled by a condition responsive switch.

A still further object of the present invention is to provide an arrangement wherein there are two thermocouples controlling the energization of a device biased to one position wherein one ther-

mo-couple is able to hold the device against the biasing means and wherein the second thermo-couple under one set of conditions aids the first thermo-couple to move the device against its bias and under other conditions opposes the first thermo-couple to release the device to its biased position.

A further object is to provide such an arrangement as set forth in the last object in which the second thermocouple is a thermo-couple having one junction capable of giving up and absorbing heat more readily than the other junction.

A still further object is to provide a system such as is set forth in the last object in which both junctions of the second thermo-couple are heated by a heater, the energization of which is controlled by a condition responsive switch.

A further object is to provide a control system, as set forth in the above objects, which has means for manual operation in the event of failure of the source of power.

Other objects will be apparent in the following specification and claims when interpreted with reference to the accompanying drawing.

The single figure of the drawing is a diagrammatic view of my invention as used in combination with a gaseous fuel burner.

The drawing shows a main burner 10 which is located in a boiler, a warm air furnace, or some other conventional heating device (not shown). The burner 10 is supplied with gaseous fuel through a pipe 11. A mixing means indicated at 12 provides for mixing gaseous fuel and air to insure a mixture having proper combustion characteristics.

The fuel supply for the burner 10 is controlled by a valve generally indicated by the reference character 13. The valve comprises a lower portion 14 and an upper portion 15. The lower portion is provided with an inlet port 16, an outlet port 17, and a partition 18 which provides a port 19 upon which the valve disc 20 is adapted to seat. Secured between the upper and lower portions 14 and 15 is a flexible diaphragm 21. Secured to the diaphragm 21 by means of the through bolt 22 is the valve disc 20 and the upper and lower plates 23 and 24, respectively, which support the center of the diaphragm 21 and the valve disc 20. A lock nut 25 is adapted to secure these members together. The through bolt 22 has an aperture 26 which allows gas to flow from the lower chamber 27 to the upper chamber 28 formed by the diaphragm 21.

Mounted upon the upper portion 15 of the valve 13 by means of the bolts 31 is a bonnet

ficient value to pull the armature 57 toward the magnetic core 58. In the modification shown, the armature 57 is sloped so that the armature 57 may be drawn into abutting engagement with the legs of the magnet core 58 and thus form a closed flux path. Therefore it is seen that it is necessary for the electromotive forces of the two thermo-couples 61 and 66 to be in the same direction and thus cooperate to pull the armature 57 into engagement with the magnet core 58.

As previously explained, when the heater 80 is first energized, the junction 70 becomes the hot junction because the normally cold junction 71 is placed within the heat insulating block 72. However, after the heater 80 has been energized for a predetermined, preferably short, period of time, the normally cold junction 71 will gradually approach the temperature of the normally hot junction 70. When the temperature of the normally cold junction 71 reaches the temperature of the normally hot junction 70, the thermo-couple will then cease to act as a generator of electromotive force and will merely serve as a conductor between the conductors 65 and 69 in the circuit of the thermo-couple 61. Therefore it is seen that the thermo-couple 66 initially assists the thermo-couple 61 in pulling in the armature 57 but shortly thereafter ceases to generate any electromotive force. However, the thermo-couple 61 may be so chosen that the electromotive force generated will be great enough to hold the armature 57 in engagement with the legs of the magnet core 58 once the armature has been moved to that position.

Therefore it is seen that this arrangement of thermo-couples provides a system whereby two thermo-couples cooperate to pull in an armature and one thermo-couple generates sufficient electromotive force to maintain the armature in that position once it has been brought to that position by the cooperation of the two thermo-couples and that the second thermo-couple loses its characteristics as an electromotive force generator shortly thereafter.

It will be noted that when the contact 104 is closed and the heater 80 is energized, the second heater 106 which is located adjacent the bimetal 101 is also energized. By energizing the second heater 106 adjacent the thermal responsive element 101 when that thermal responsive element is in position calling for heat, there will be a tendency to supply artificial heat as well as ambient heat to the bimetal. In other words, when the contact 104 is made and is calling for heat, the heater 106 adjacent the bimetal is energized and therefore will heat the bimetal 101 and thus tend to separate the blade 102 and the contact 104 before such separation would occur solely by reason of a rise in ambient temperature. Therefore it will be seen that the result will be to shorten the time of the "burner on" period and thus tend to compensate for the lag in the heating system in connection with the delivery of heat to the vicinity of thermostat 100.

When the thermostatic blade 102 moves away from the contact 104, the electrical circuit which supplies energy to the heater 80 will be opened. Prior to the opening of the contact 104, the heater 80 had been energized and had heated the junctions of the thermo-couple 66 up to substantially the same value. However, when the heater 80 is deenergized, there will be a tendency for the normally hot junction 70 and the normally cold junction 71 to cool down to the ambient temperature. However, in cooling, the 75

normally cold junction 71 will cool off at a substantially slower rate than the normally hot junction and will serve now as a hot junction rather than as a cold junction as it did when heating up in response to the heat generated by the heater 80. Therefore it is seen that the electromotive force now generated by the thermo-couple 66 will be in a direction opposite to the electromotive force which is generated by the thermo-couple 61. When the reverse electromotive force generated by the insulated junction 71 reaches a value which is substantially equal and opposite to the electromotive force generated by the thermo-couple 61, the total electromotive force applied to the field winding of the electromagnet will be negligible. Therefore the flapper valve 55 will move toward the left by the action of the spring 54 to a position to close the bleed port 50.

20 In the event the pilot flame issuing from the pilot burner 41 is extinguished, a dangerous condition would result if the valve 20 were open to admit gas to the main burner 10. When the flame is extinguished, the thermo-couple 61 will be generating no electromotive force to energize the field winding 59. However, if the temperature in the space falls, the thermostat 100 will close the contact 104 and thus energize the heater 80, and by energizing the heater 80 will establish an electromotive force in the field winding 59 by the action of the thermo-couple 66. The thermo-couple 66 is adapted, on heating, to generate sufficient electromotive force to actuate the flapper valve 55. However, shortly after sufficient electromotive force has been generated to actuate the flapper valve, the normally cold junction 71 of the thermo-couple 66 will have heated up to substantially the same temperature as the normally hot junction 70 thus causing the electromotive force to drop to a negligible value, therefore allowing the armature 57 to move away from the magnet core 58 and thus close the bleed port 50. It is seen that the flapper valve will have actually been away from the port 50 for only a very short period of time. During this time an insufficient amount of gas will be allowed to escape through the bleed port 50 to allow the valve 20 to move away from its seat 19 and, therefore, the valve 20 cannot open when the pilot flame is 45 extinguished.

50 In the event of failure of power supply in the line conductors 90 and 91, it may be desired to actuate the valve 13 between open and closed positions. Therefore the valve opening push rod 44 is provided to move the flapper valve 55 away from the bleed port 50 to open the valve 20, and the push rod 45 is provided to push the flapper valve 55 into engagement with the bleed port 50 to close the valve 20. When the flapper valve 55 is pushed away from the bleed port 50 by the push rod 44, the armature 57 will engage the magnet core 58 and the pilot burner in cooperation with the thermo-couple 61 will generate enough electromotive force across the field winding 59 to maintain the flapper valve 55 away from the bleed port 50 until such time as it is desired to close the valve which is accomplished by pushing the flapper valve 55 into engagement with the bleed port 50 by pressing the push rod 45.

70 It will be noted that the existence of a pilot flame is necessary to accomplish the manual operation of the valve 20 because it is essential that there be a flow of electric current through the field winding 59 to maintain the flapper valve 55

in a position away from the bleed port 50. Therefore, if the pilot flame issuing from the pilot burner 41 is extinguished there will be no electro-motive force generated in the junction 63 of the thermo-couple 61 and the flapper valve 55 will be moved by the spring 54 to a position closing the bleed port 50.

It is seen that I have provided a control system which is simple and economical of structure and fool-proof in operation, that is applicable in controlling a condition and is responsive to a second condition which may modify control. Many forms and applications of this invention will occur to those skilled in the art, therefore it should be clearly understood that I am not to be limited in my invention to the preferred form shown and described but by the scope of the appended claims.

I claim as my invention:

1. In a control system, an armature, an electromagnet cooperating with said armature, a first thermo-couple responsive to a thermal condition and controlling the energization of said electromagnet, said first thermocouple being capable of energizing said electromagnet in a value sufficient to hold said armature in a position adjacent said electromagnet when the condition exists but incapable of performing the same function when the condition is non-existent and incapable of independently pulling said armature into a position adjacent said electromagnet, a second thermo-couple, an electric heater adapted to affect said second thermo-couple, an electric switch, a source of electric power controlled by said switch for supplying electric current to said heater, said second thermo-couple having a first junction capable of quickly absorbing and giving up heat and a second junction capable of only slowly absorbing and giving up heat, the first junction of said second thermo-couple being adapted to cooperate with said first thermo-couple to pull said armature into a position adjacent said electromagnet and the second junction of said second thermo-couple being adapted to oppose said first thermo-couple sufficiently to allow said armature to drop out of engagement with said electromagnet.

2. In a control system, an armature, an electromagnet cooperating with said armature, a first thermo-couple responsive to a thermal condition and controlling the energization of said electromagnet, said first thermocouple being capable of energizing said electromagnet in a value sufficient to hold said armature in a position adjacent said electromagnet when the condition exists but incapable of performing the same function when the condition is non-existent and incapable of independently pulling said armature into a position adjacent said electromagnet, a second thermo-couple, a first electric heater adapted to affect said second thermo-couple, a thermostatic switch, a source of electric power controlled by said switch for supplying electric current to said heater, a second electric heater adjacent said thermostatic switch and adapted to affect the same simultaneously said first heater is energized in a manner to substantially diminish the time that said first heater will be energized, said second thermo-couple having a first junction capable of quickly absorbing and giving up heat and a second junction capable of only slowly absorbing and giving up heat, the first junction of said second thermo-couple being adapted to cooperate with said first thermo-couple to pull said armature into a position adjacent said electromagnet and the second junction of said second thermo-couple being adapted to oppose said first thermo-couple sufficiently to allow said armature to drop out of engagement with said electromagnet.

ture into a position adjacent said electromagnet and the second junction of said second thermo-couple being adapted to oppose said first thermo-couple sufficiently to allow said armature to drop out of engagement with said electromagnet.

3. In a fluid fuel burner control system, a fluid fuel burner, ignition means adjacent said fuel burner adapted to thermally ignite fuel issuing from said burner, fuel supply means adapted to deliver fuel to said burner, control means to provide a "burner on" condition and a "burner off" condition, a first thermo-couple electrically connected to said control means and thermally responsive to the ignition means, a second thermo-couple having a hot junction and a heat insulated cold junction electrically connected to said first thermo-couple and said control means, the hot junction of said second thermo-couple being adapted to cooperate with said first thermo-couple to place the control means in "burner on" condition and the cold junction of said second thermo-couple being adapted to oppose said first thermo-couple to place the control means in "burner off" condition, a source of electric power, an electric heater adjacent said second thermo-couple and adapted to supply heat thereto, and a thermostat controlling the electric circuit to said heater.

4. In a fluid fuel burner control system, a fluid fuel burner, ignition means adjacent said fuel burner adapted to thermally ignite fuel issuing from said burner, fuel supply means adapted to deliver fuel to said burner, control means to provide a "burner on" condition and a "burner off" condition, a first thermo-couple electrically connected to said control means and thermally responsive to the ignition means, a second thermo-couple having a hot junction and a heat insulated cold junction electrically connected to said first thermo-couple and said control means, the hot junction of said second thermo-couple being adapted to cooperate with said first thermo-couple to place the control means in "burner on" condition and the cold junction of said second thermo-couple being adapted to oppose said first thermo-couple to place the control means in "burner off" condition, a source of electric power, an electric heater adjacent said second thermo-couple and adapted to supply heat thereto, a thermostat controlling the electric circuit to said heater, and manual means to actuate said control means in the event of failure of the source of electric power.

5. In a fluid fuel burner control system, a fluid fuel burner, a pilot burner adjacent said fuel burner, a valve controlling the supply of fuel to said fuel burner, valve actuating means adapted to open and close said valve, a first thermo-couple electrically connected to said valve actuating means and responsive to the existence of a pilot flame, said first thermo-couple being adapted to generate an electromotive force only when the pilot flame is burning and in a value only sufficient to maintain said valve actuating means in "burner on" position after said valve actuating means have been moved to that position and unassisted said first thermo-couple generates insufficient electromotive force to move said valve actuating means to "burner on" position, a second thermo-couple having a hot junction and a heat insulated cold junction electrically connected to said valve actuating means and said first thermo-couple, the hot junction of said second thermo-couple being adapted to cooperate with said first thermo-couple to place the control means in "burner on" condition and the cold junction of said second thermo-couple being adapted to oppose said first thermo-couple to place the control means in "burner off" condition.

with said first thermo-couple to move said valve actuating means to "burner on" position and the cold junction of said second thermo-couple being adapted to oppose said first thermo-couple to allow said valve actuating means to move to "burner off" position, a source of electric power, a first electric heater, a thermostat being adapted to energize said first heater when the temperature being controlled reaches a predetermined low value, a second heater adjacent said thermostat being adapted to supply heat to said thermostat when the circuit to said first heater is energized thus tending to open said circuit and shorten the "burner on" periods, and manual means to open and close said fuel supply valve in the event of failure of the source of electric power.

6. In a fluid fuel burner control system, a fluid fuel burner, a pilot burner adjacent said fuel burner, a valve controlling the supply of fuel to said fuel burner, valve actuating means adapted to open and close said valve, electromagnetic means cooperable with said valve actuating means, a first thermo-couple electrically connected to said electromagnetic means and responsive to the existence of a pilot flame, said first thermo-couple being adapted to generate an electromotive force only when the pilot flame is burning and in a value only sufficient to maintain said valve actuating means in "burner on" position after said valve actuating means have been moved to that position and unassisted said first thermo-couple being capable of generating insufficient electromotive force to move said valve actuating means to "burner on" position, a second thermo-couple having a hot junction and a heat insulated cold junction electrically connected to said electromagnet and said first thermo-couple, the hot junction of said second thermo-couple being adapted to cooperate with said first thermo-couple to move said valve actuating means to "burner on" position and the cold junction of said second thermo-couple being adapted to oppose said first thermo-couple to allow said valve actuating means to move to "burner off" position, a source of electric power, a first electric heater, a thermostat being adapted to energize said first heater when the temperature being controlled reaches a predetermined low value, a second heater adjacent said thermostat being adapted to supply heat to said thermostat when the circuit to said first heater is energized thus tending to open said circuit and shorten the "burner on" periods, and manual means to open and close said fuel supply valve in the event of failure of the source of electric power.

7. In a fluid fuel burner control system, a fluid fuel burner, a pilot burner adjacent said fuel burner, a valve controlling the supply of fuel to said fuel burner, a pressure motor adapted to open and close said valve, a bleed port controlling the action of said pressure motor, a flapper valve cooperating with said bleed port, an electromagnet adapted to cooperate with said flapper valve, a first thermo-couple electrically connected to said electromagnet and responsive to the existence of a pilot flame, said first thermo-couple being adapted to generate an electromotive force only when the pilot flame is burning and in a value only sufficient to maintain said flapper valve away from said bleed port after said flapper valve has been moved to that position and said first thermo-couple independently generating insufficient electromotive force to move said flapper valve out of engagement with said

bleed port, a second thermo-couple having a hot junction and a heat insulated cold junction electrically connected to said electromagnet and said first thermo-couple, the hot junction of said second thermo-couple being adapted to cooperate with said first thermo-couple to move said flapper valve away from said bleed port and the cold junction of said second thermo-couple being adapted to oppose said first thermo-couple to allow said flapper valve to close said bleed port, a first electric heating element in heat transfer relationship to said second thermo-couple, a source of electric power, a thermostat being adapted to energize said first heater when the temperature being controlled reaches a predetermined low value, a second electric heater adjacent said thermostat which supplies heat to said thermostat when the circuit to said first heater is energized thus tending to open said circuit and shorten the "burner on" periods, and manual means to open and close said fuel supply valve in the event of failure of the source of electric power.

8. In a control system, an armature, an electromagnet cooperating with said armature, a first thermo-couple responsive to a thermal condition and controlling the energization of said electromagnet, said first thermocouple being capable of energizing said electromagnet sufficiently to hold said armature in a position adjacent said electromagnet when the condition exists but incapable of performing the same function when the condition is nonexistent and incapable of independently pulling said armature into a position adjacent said electromagnet, a second thermo-couple, means for effecting a temperature differential between the junctions of said second thermocouple to produce an electromotive force of such direction and intensity that said second thermocouple will assist said first thermocouple in pulling said armature into engagement with said electromagnet, and further means to provide a reversal in direction of the electromotive force generated by said second thermocouple whereby said second thermocouple will oppose said first thermocouple to allow said armature to drop out of engagement with said electromagnet.

9. In a control system, an armature, an electromagnet cooperating with said armature, a first thermocouple responsive to a thermal condition and controlling the energization of said electromagnet, said first thermocouple being capable of energizing said electromagnet sufficiently to hold said armature in a position adjacent said electromagnet when the condition exists but incapable of performing the same function when the condition is nonexistent and incapable of independently pulling said armature into a position adjacent said electromagnet, a second thermo-couple, means for effecting a temperature differential between the junctions of said second thermocouple to produce an electromotive force of such direction and intensity that said second thermocouple will assist said first thermocouple in pulling said armature into engagement with said electromagnet, further means to provide a reversal in direction of the electromotive force generated by said second thermocouple whereby said second thermocouple will oppose said first thermocouple to allow said armature to drop out of engagement with said electromagnet, and condition responsive means for controlling said temperature differential effecting means.

10. In a control system, an armature, an electromagnet cooperating with said armature, a first thermocouple responsive to a thermal condition and controlling the energization of said electro-

magnet, said first thermocouple being capable of energizing said electromagnet sufficiently to hold said armature in a position adjacent said electromagnet when the condition exists but incapable of performing the same function when the condition is nonexistent and incapable of independently pulling said armature into a position adjacent said electromagnet, a second thermocouple, means for effecting a temperature differential between the junctions of said second thermocouple to produce an electromotive force of such direction and intensity that said second thermocouple will assist said first thermocouple in pulling said armature into engagement with said electromagnet, further means to provide a reversal in direction of the electromotive force generated by said second thermocouple whereby said second thermocouple will oppose said first thermocouple to allow said armature to drop out of engagement with said electromagnet, condition responsive means for controlling said temperature differential effecting means, and means associated with said condition responsive means for modifying the controlling operation thereof.

11. In combination with a plural position electrically actuated device, a first thermo-electric current generating means responsive to a condition to produce an electromotive force sufficient to maintain said device in one position but insufficient to move it from one to another position, a second thermo-electric current generating means responsive to a controlled condition to produce a selectively reversible electromotive force, and connecting means between said generating means and said device whereby said two generators cooperate to produce an electromotive force to move said device to one position wherein it is maintained by said first generating means and said second generating means will oppose said first generating means to produce a counter-electromotive force to cause said device to move to another position.

12. In combination, an armature, an electromagnet cooperating with said armature, a first thermocouple, a second thermocouple, means associated with said second thermocouple to create a temperature differential between the junctions thereof to cause said second thermocouple to generate an electromotive force in a direction and of such intensity that said second thermocouple will assist said first thermocouple to pull said armature into engagement with said electromagnet, and further means to change the direction of the electromotive force generated by said second thermocouple to cause said force to effectively oppose the electromotive force generated by said first thermocouple to allow said armature to drop out of engagement with said electromagnet.

13. In combination, an armature, an electromagnet cooperating with said armature, a first thermocouple, a second thermocouple, means associated with said second thermocouple to create a temperature differential between the junctions thereof to cause said second thermocouple to generate an electromotive force in a direction and of such intensity that said second thermocouple will assist said first thermocouple to pull said

5 armature into engagement with said electromagnet, further means to change the direction of the electromotive force generated by said second thermocouple to cause said force to effectively oppose the electromotive force generated by said first thermocouple to allow said armature to drop out of engagement with said electromagnet, and condition responsive means for controlling the operation of said last means.

10 14. In combination, an armature, an electromagnet cooperating with said armature, a first thermocouple, a second thermocouple, means associated with said second thermocouple to create a temperature differential between the junctions thereof to cause said second thermocouple to generate an electromotive force in a direction and of such intensity that said second thermocouple will assist said first thermocouple to pull said armature into engagement with said electromagnet, further means to change the direction of the electromotive force generated by said second thermocouple to cause said force to effectively oppose the electromotive force generated by said first thermocouple to allow said armature to drop out of engagement with said electromagnet, condition responsive means for controlling the operation of said last means, and means associated with said condition responsive means for modifying the controlling operation thereof.

20 15. In combination, an electrically actuated device movable between first and second positions, a member controlled by said device, a first thermocouple responsive to a condition that is substantially constant when present, said first thermocouple being operable to produce a substantially constant electromotive force in one direction, a second thermocouple responsive to a controlled condition, said second thermocouple being operable to produce a reversible electromotive force substantially equal in either direction to the electromotive force produced by said first thermocouple, and connecting means between said thermocouples and said device whereby said two thermocouples cooperate in producing an electromotive force sufficient to move said device to said first position and oppose each other in producing electromotive force to move said device to said second position.

30 16. In combination with a two position electrically actuated device, a first electromotive force generator responsive to a condition to produce a substantially constant electromotive force in one direction sufficient to maintain said device in one position but insufficient to move it from one to the other position, a second electromotive force generator responsive to a controlled condition to produce a selectively reversible electromotive force, and connecting means between said generators and said device whereby said two generators cooperate to produce an electromotive force to move said device to one position wherein it is maintained by said first generator and said second generator will oppose said first generator to produce a counter-electromotive force to cause said device to move to its other position.

FREDERICK E. LANGE.
